DIGITAL MULTIMETER

Derek David Roberts, Berkhamsted, England, assignor to
The Solartron Electronic Group Ltd., Farnborough,
England

Filed Jan. 20, 1975, Ser. No. 542,399

Claims priority, application United Kingdom July 27, 1974

Term of patent 14 years

Int. Cl. D10—04

U.S. Cl. D10—57

FIG. 1

FIG. 2

FIG. 3

FIG. 1 is a front perspective view of a digital multimeter, showing my new design;

FIG. 2 is a right side elevational view thereof;

FIG. 3 is a rear elevational view thereof.

The bottom of the instrument is substantially plain and unornamented.

I claim:

The ornamental design for a digital multimeter, as shown and described.
